PUMP

Clement J. Welling, Tulsa, Okla., assignor of ten
per cent to May Welling, Tulsa, Okla.

Application December 1, 1945, Serial No. 632,256

9 Claims. (Cl. 103—166)

1

This invention relates to pumps, and more particularly to a cylindrical sleeve-type pump for pumping oil, water, and other liquids.

It is an object of the invention to provide a novel pump, primarily a bottom-hole pump, adapted for oil well pumping, water well pumping, irrigation pumping, bilge pumps for marine service, pipe line pumping, chemical process pumping, and many other pumping uses.

A still further object of the invention is to provide a bottom hole pump for oil wells, or the like, or a fluid pump for pumping various types of liquids, assisted by the hydraulic action in the bottom of the hole or well and non-compressibility of the liquid, to cause the fluid around the pump to be forced out and up with the column of fluid in the casing, pipe or tubing, either being used.

Another object of the invention is to provide a pump of the character described which is relatively simple in construction, which, therefore, comprises a minimum number of parts and is adaptable to a viscous fluid; will require a minimum amount of non-productive time in servicing and upkeep; and can be produced economically, be serviced at a minimum cost without requiring the employment of highly trained mechanics, and is durable and efficient in use.

Other objects and advantages reside in the details of construction and operation as more fully hereinafter described and claimed, reference being had to the accompanying drawings forming part hereof, wherein like reference numerals refer to like parts throughout, and in which:

Figure 1 is a sectional elevation showing the positions of the pump plungers or pistons at the bottom of the stroke.

Figure 2 is a similar view showing the plungers or pistons on the upstroke.

Figure 3 is a similar view showing the plungers or pistons in a further position on the upstroke.

Figure 4 is a similar view showing the plungers or pistons at the top of the upstroke.

Figure 5 is a similar view showing the pistons on a downstroke, and

Figure 6 is a similar view showing the pistons at the bottom of the downstroke.

Referring to the drawings in detail, the pump is shown in connection with the bottom of a well, in which 10 designates the wall around the hole 11 and casing 12. The bottom of the casing is closed by a packer or packing ring 13 which is set in the casing 12 with its top edge set on a level with the bottom edge of the outlet port in the pump sleeve, as will be hereinafter pointed

2

out, and its bottom edge flush or substantially flush with the lower end of the casing, but sufficiently narrow not to cover the inlet port of the pump sleeve or cylinder, and therefore not necessarily flush with the bottom edge of the casing, as long as it does not cover the inlet port. Disposed within the casing so as to extend down into the bottom hole of the well, is a cylindrical pump sleeve, cylinder or barrel 14 closed at the top by a sleeve cap or plug 15 vented as indicated at 15' to relieve pressure and vacuum at different stages of the cycle of the pump and at the bottom by a similar sleeve cap or plug 16 within the well bottom 11 and similarly vented as indicated at 16'. A pull rod 17 extends down from the surface in the casing 12 and is adapted for connection with any suitable prime-mover, which can be any conventional mechanical, electrical, or other operating device acceptable to its particular adaptation for actuating the same by a vertical reciprocation thereof. The lower end of the pull rod 17 is provided with a reduced portion 18, providing a shoulder 19 and having its lower end threaded or otherwise provided, as indicated at 20, for connection with the upper end of a lower plunger or piston 21 which operates in the lower portion of the sleeve or cylinder 14, to the bottom cap or closure plug 16.

Immediately above the upper end of the piston or plunger 21 when in its lowest position, the cylinder or sleeve 14 is provided with inlet ports 22 through its wall on opposite sides, diametrically opposite each other, and immediately above an intermediate wall portion 23 is provided. Sealing device or packing ring 13 is held in bore 24 of casing 12 at its lower end. The sleeve 14 is held in the axial opening 25 in the sealing device or packing ring 13 closing the lower end of the casing 12. Immediately above the packing ring or plug 13 the sleeve or cylinder 14 is provided with diametrically opposite outlet ports 26. The relation of these ports is such that the top edge of the packing 13 in the casing 12 is on a level with the bottom edges of the outlet ports 26 while the packing 13 is narrow enough not to cover the inlet ports 22 below the same and the wall portion 23 intermediate the inlet ports 22 and the outlet ports 26.

Mounted on the pull rod 17 and movable or slidable relative thereto is an upper piston or plunger 27 having a relatively short upper enlarged bore portion 28 which receives the lower end of the pull rod. This provides a shoulder 29 at the upper end of a reduced bore 30 below the enlarged bore 28 and through the lower portion

of the plunger or piston 27 which bore receives the reduced portion 18 of the pull rod 17 therethrough for connection with the upper end of the piston or plunger 21. A passage or space 31 is provided between the pistons 21 and 27 adapted to be aligned with the diametrically opposed inlet ports 22 at the bottom of the stroke, and also adapted to be closed by upward movement of the lower piston or plunger 21 with the pull rod 17, part of said upward movement being relative to 10 the upper piston or plunger 27, as will be herein-after explained.

The shoulder 19 is adapted to engage the shoulder 29 formed between or at the juncture of the enlarged bore portion 28 and the reduced 15 bore portion 30, when both pistons are at the bottom of the stroke both initially and at the lower end of the downward stroke, as indicated in Figures 1 and 6 of the drawings.

Thus, in the operation of the pump, on the 20 upstroke of the pull rod, with the upper piston 27 and the lower piston 21 straddling the inlet ports 22 through which fluid passes between the pistons, both pistons are pulled or moved upwardly and the pistons will remain apart or separated because of the lack of compressibility of the fluid between the pistons in the cylinder or sleeve 14. The lower piston 21, as shown in Figure 2, will therefore move upwardly to close the inlets 22 and lift the fluid therewith upwardly through the intermediate wall portion 23, during which movement the upper piston 27 will also move upwardly therewith by reason of the column of fluid between the pistons retaining engagement of the shoulder 29 with the shoulder 19 of the pull rod. In this connection, it is pointed out that the bore of the sleeve or cylinder 14 is enlarged at the upper portion as indicated at 32 to form an upwardly facing shoulder 33 with and at the upper end of the lower reduced bore portions 34 of the sleeve 14 at wall 23 and the wall portions of the lower portion of the sleeve or cylinder 14 below the inlet ports 22, as well as a short distance above the outlet ports 26. The upper portion of the piston or plunger 27 is enlarged relative to the lower portion, to provide a downwardly facing shoulder 35 which, at the bottom of the downstroke, is adapted to engage the shoulder 33 facing upwardly by reason of the enlarged bore portion 32 of the sleeve or cylinder 14. However, on the upstroke, as shown in Figure 2 of the drawings, the piston 27, supported by the wall of fluid between the pistons 21 and 27, will move upwardly, when the shoulder 35 will move away from the shoulder 33, during which time the piston 27 continues to maintain the ports 26 closed, while the piston 21 moves upwardly and closes the inlet ports 22. Upon continued upward movement, as shown in Figures 3, on the upstroke, the piston 21 continues to maintain the inlet ports 22 closed, while the upper piston 27 is moved upwardly with the pull rod above and past the outlet ports 26 until the piston 27 reaches the closed upper end or plug 15 of the cylinder or sleeve 14 and the liquid between the two pistons is discharged into the casing 12 or lifted from the well hole 11 to the casing. Thus, the lower piston closes the inlet ports and the pistons both have reached their maximum height with the 70 space 31 communicating with the outlet ports 26. Upon continued upward movement of the pull rod to the top of the stroke, as shown in Figure 4 of the drawings, the upper piston 27 having reached the limit of its movement upward, by 75

engagement with the plug 15 as seen in Figure 3, the portion of the pull rod above the reduced portion 18 will continue its upward movement in the enlarged bore portion 28, drawing the lower piston 21 with it until piston 21 reaches the limit of its movement upward by engagement with the lower end of the piston 27, when the liquid in the space 31 between the pistons will be discharged into the casing 12. That is, when the upper piston 27 is in its highest position on the upward stroke of the pull rod, the lower piston 21 is pulled up until its upper end is adjacent the lower end of the upper piston 27, thus closing space 31 and forcing the fluid out into the casing from the cylinder.

This action, instead of causing the liquid to be discharged from the cylinder back through the inlet ports into the well, is explained by the fact that the pump is primarily a bottom hole pump for oil wells or other wells in which the liquids in the well are maintained under pressure. The hydraulic action in the bottom of the well is such that a pressure is exerted on the fluid around the pump and since the oil, water, or other liquid, has little or no compressibility, the pressure will force the upper piston upward until the lower piston covers the inlet ports. In the average well, the hydraulic pressure is equal to the weight of the column of the fluid in the casing from the surface to the bottom of the hole plus 10% or other proportion, depending upon the circumstances. This, therefore, exerts a greater pressure of the liquid in the well and at the inlet ports against the lesser pressure at the outlet ports and in the casing subject to the pressure head of the column of liquid in the casing and the atmospheric pressure acting thereon. There are several reasons for the phenomena, one of them being a pronounced water drive, which means pressure of water against the oil formation in the case of oil wells, or pools, or of water, as in the case of water or artesian wells. In some cases, the oil formation is in underground slopes, and the pump is submerged in the fluid deep enough so that a static head is formed. In other cases, there is a gas pressure on the oil, causing the oil to follow the line of least resistance, which is the inlet or inlet ports on the lower part of the pump. Thus, this pressure exceeds the pressure acting on the column in the casing or pressure head thereof.

Thus, the liquid will be discharged into the casing and raised therein for discharge.

On the downstroke, as shown in Figure 5 of the drawings, the upper piston and the lower piston, because of the weight of the upper piston, remain adjacent to each other or in contact until the shoulder 34 of the upper piston engages the shoulder 33 in the cylinder or sleeve 14 opposing the same, when the weight of the pull rod starts the separation of the pistons and causes the continued downward movement of the lower piston 21 to the position shown in Figure 6, spaced from the lower end of the upper piston 27 as also shown in Figure 1, when the space 31 therebetween will be aligned with the inlet ports 22 for continuation of the cycle of operation, as previously described, on the upward stroke of the pull rod.

Thus, it will be seen that I have provided a pump of extreme simplicity with a minimum number of parts and great flexibility of use, in that it is adapted to any viscous fluid and may be maintained in operative condition with a minimum amount of non-productive time in servic-

ing the pump. It is also economical in cost, to produce, service and maintain in properly operative condition, since there is no need for highly trained mechanics in order to accomplish this fact.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired, as well as in the type of material.

While a pump casing 12 is referred to it is to be understood that either a casing, pipe or tubing may be used, since ordinarily, an oil well pump is inserted in the tubing or inner string which is surrounded by the casing or outer string, the idea being that common practice is for the pump to be in the tubing, but it is applicable as a tubing or casing pump. Also the sealing device, packing ring or apertured plug 13, may be any one of several types, notably, a three-cup hold down, which is used for inserting the pump in the bottom of a string of tubing. It is standardized and both the hold down and the pump should be held within American Petroleum Institute specifications, while the upper and lower ends of the pump cylinder may be vented in any suitable manner.

Having thus described the invention, what I claim is:

1. A force pump comprising a casing, a packing in the lower end of the casing, a cylinder having substantially closed upper and lower ends held in said packing, inlet ports in said cylinder below the packing and outlet ports in said cylinder above the packing, a pull rod extending into the cylinder, a lower piston in the cylinder fixed to the lower end of the rod, an upper piston slidably disposed on the pull rod, means in said cylinder for retaining said upper piston above the inlet ports when the lower piston is seated on the lower end of the cylinder below the inlet ports to allow fluid to enter the cylinder between the upper and lower pistons, and complementary means in the upper piston and rod for limiting upward movement of the upper piston on the rod to maintain the pistons in a spaced placement when the pistons are pressurized upwardly, said lower piston moving relative to the upper piston upon engagement of the upper piston with the upper end of the cylinder to force the fluid retained between the pistons through the outlet ports into the casing.

2. A force pump comprising a casing, a packing in the lower end of the casing, a cylinder, having substantially closed upper and lower ends, held in said packing, inlet ports in said cylinder below the packing and outlet ports in said cylinder above the packing, a pull rod extending into the cylinder, a lower piston in the cylinder fixed to the lower end of the pull rod, an upper piston slidably mounted on the pull rod, means in said cylinder above the outlet ports for engaging complementary means carried by the upper piston for retaining said upper piston above the inlet ports when the lower piston is seated on the lower end of the cylinder to allow fluid to enter the cylinder between the upper and lower pistons, and complementary means in the upper piston and the pull rod for limiting upward move-

ment of the upper piston on the rod relative to the lower piston when the pistons are pressurized upwardly, said lower piston moving into abutting engagement of the upper piston upon engagement of the upper piston with the upper end of the cylinder to discharge fluid from between the pistons through the outlet ports.

3. In a force pump, the combination with a well tubing having a bottom packing ring, a cylinder having substantially closed upper and lower ends, held in said ring, inlet ports in said cylinder below the ring and outlet ports in said cylinder above the ring, a pull rod extending into the cylinder, a lower piston in the cylinder fixed to the lower end of the rod, an upper piston slidably mounted on the pull rod, complementary shoulders on said cylinder and said upper piston for engagement to retain the upper piston above the inlet ports when the lower piston is lowered to a seated placement on the lower end of the cylinder below the inlet ports whereby fluid enters the cylinder between the pistons, and complementary means carried by the upper piston and rod for coactive engagement to limit upward movement of the upper piston on the rod when the pistons are pressurized upwardly, said lower piston moving relative to the upper piston upon engagement of the upper piston with the upper end of the cylinder to force the fluid retained between the pistons thru the outlet ports into the casing.

4. A force pump comprising the combination with a well tubing having a packing ring in the lower end thereof of a cylinder held in said ring and extending above and below the same, said cylinder having inlet ports below the ring and outlet ports above the ring, a pull rod extending through the cylinder, a lower piston fixed on the lower end of the pull rod, an upper piston slidably mounted on the pull rod, an upwardly facing shoulder on the cylinder above the ring, a downwardly facing annular shoulder on the upper piston adapted to engage the shoulder on the cylinder to retain the upper piston above the inlet ports when the lower piston is lowered to a seated placement on the bottom of the cylinder whereby fluid enters the cylinder between the pistons, and complementary means carried by the upper piston and the rod for coactive engagement to limit the upward movement of the upper piston on the rod when the pistons are pressurized upwardly whereby the pistons are disposed on the rod in spaced relation, said lower piston moving relative to abutting placement with the upper piston to force the fluid from between the pistons through the outlet ports into the ring tubing.

5. The combination of claim 2, wherein said pull rod includes an upper section and a lower coaxially reduced section defining a downwardly facing shoulder and means carried by said upper piston for engaging said shoulder to limit upward movement of the upper piston on the rod.

6. The combination of claim 5, wherein said means includes a vertical bore in said piston to receive the pull rod, an annular shoulder in said bore adapted to engage the pull rod shoulder.

7. A force pump comprising a well casing having a bottom packing ring, a cylinder held in said ring and having a substantially closed upper and lower end, inlet ports in said cylinder below the ring and outlet ports in said cylinder above the ring, a pull rod extending into the cylinder, said rod having an upper portion and a coaxially reduced lower portion defining a downwardly facing

shoulder, a lower piston fixed on the lower portion of the pull rod, an upper piston slidably mounted on the upper and lower portions of the rod, means carried by said piston for engaging the rod shoulder to limit upward movement of the upper piston on the rod, an exterior annular shoulder on said upper piston, and an upwardly facing shoulder on said cylinder adjacent the packing ring, said annular piston shoulder being seated on the cylinder shoulder to retain the upper piston above the inlet ports when the lower piston is received on the lower end of the cylinder whereby fluid entering the cylinder is received between the pistons, said lower piston moving responsive to an upward pressure thrust relative to the upper piston upon engagement of the upper piston with the upper end of the cylinder to force the fluid retained between the pistons thru the outlet ports into the casing.

8. The combination of claim 7, wherein vents are provided in the upper and lower ends of the cylinder.

9. A force pump including a well casing, having a bottom packing ring, a cylinder, having a vented upper and lower end, held in said ring, inlet ports in said cylinder below the ring, outlet ports in said cylinder above the ring, a pull rod extending into the cylinder, a lower piston in the cylinder fixed to the lower end of the rod, an upper piston slidably mounted on the rod, 30

means in said cylinder for complementary engagement of means carried by the upper piston for retaining said upper piston above the inlet ports upon seatment of the lower piston on the lower end of the cylinder whereby fluid entering the cylinder is received between the pistons, said upper piston having a central bore therein for receiving the pull rod, an upwardly facing shoulder in said bore, a downwardly facing complementary shoulder on said rod, said shoulders engaging to limit upward movement of the upper piston on the rod upon upward pressurized movement of the pistons relative to the outlet ports, said upper piston abutting against the upper end of the cylinder to brake the ascent of the pistons and said lower piston moving relative to the upper piston forcing the rod shoulder upwardly from its seat on the upper piston whereby fluid is forced from between the pistons through the outlet ports.
